Application December 1, 1942, Serial No. 467,550

3 Claims. (Cl. 214—122)

The present invention relates to mine hoisting machinery and more particularly to improvements in the cages.

In the development of mines, vertical shafts are to a large extent used in which to hoist material and workmen. Many of these shafts have been in existence a number of years, originally made to dimensions suitable for accommodating wooden mine cars as then made, when material and labor was cheap. These shafts are equipped, at great expense, with upright cage guides supported by bunters or other timbers, so that to enlarge the shafts would require considerable time and expense. The urgent demand for material, such as coal, has made it essential to deliver from the mines increasing quantities thereof during a given period of time and also because of the higher cost of mine haulage and labor, improved mine cars of metal have been provided mainly to increase the load capacity as compared with the wooden cars. In this way the output of mines has been gradually increased over a period of years, still using shafts of the size made many years ago. The overall dimensions of these improved cars have, in the past, been limited by characteristics of the cages running in the shafts, some of which have been in use for many years or patterned after those used when wooden cars were standard. To increase the size of the shafts and install guides and other equipment would be expensive and result in the mine being idle if only one shaft is available, or reduce the producing capacity of the mine if more than one shaft is available and they are, one by one, altered for accommodation of cars of larger overall dimensions.

Until recently the effort has been to increase the capacity of the cars by providing running gear which avoids "thru" axles and to arrange the car bottoms so that some of the material may be nested, so to speak, in portions of the bottoms about the upper portions of the wheels, using every available space in the car body for the lading. The point was finally reached where such construction practically reached the limit, and further efforts along these lines led to complicated and expensive car construction. It was finally determined that the best procedure to increase the load capacity of the car, would be to increase its body width, especially for cars used in new mines where shafts of larger dimensions were available for accommodating them. Such improved cars met with such favor that proprietors of the older mines realized that the cost of production according to available equipment in their mines was greater than in the newer mines but that the great demand for coal did not justify closing the mines to make the expensive alterations.

The present invention has for its principal object, the provision of an improved mine cage

which allows just sufficient clearance between the cage and the hoist frame (sometimes called the "sling" or "bridle"), and just sufficient clearance between the sides of the cage and the car body, consistent with safety and speed of operation, to permit the use of the wider cars in the older mines without increasing the plan dimensions of the hoistway.

Another object of the invention is to provide an improved mine cage for the wider mine cars of the character described and which may be used with the dumping track in the head-frame of the head-house of the older mines, for dumping of the cars, without altering the gauge of the tracks or in any way reconstructing or rearranging the said track.

A further object of our invention is to provide a mine cage which is inexpensive to manufacture and maintain in good repair. It may be made mainly of sheet metal, standard rolled metal sections and metal bars, and conveniently welded together to provide a strong and comparatively light cage susceptible of withstanding the stresses and strains to which industrial equipment of this kind is subjected in practice.

Other objects and advantages of this invention will be apparent from the following detailed description, taken in connection with the accompanying drawings, forming a part of this specification, and in which drawings:

Figure 1 is a view in side elevation of a cage constructed according to the present invention, there also being shown a portion of one of the guides and one of the sets of guide rails of the dumping track common in the art.

Figure 2 is an end elevation of the cage, portions of the hoist frame being broken away to disclose some details.

Figure 3 is an enlarged view partly in plan and partly in horizontal section looking down upon the hoist frame and a portion of the cage.

Figure 4 is an enlarged view in elevation of the upper portion of the hoist frame and cage.

By way of example, the drawings show opposite vertical stationary guides 1, such as are found in many mine shafts in this country; a hoist frame 8 also common in the art, held to a predetermined path of travel in the shaft by guides 7; and a dumping track 9, in Figure 1, such as is found in the head-frames of shafts, for tilting the cage when it is desired to dump the load from a mine car 10, shown in Figure 2, resting upon the improved cage 11. In the drawings there are also shown, by way of example, the ordinary flanged dumping wheels 12 carried by cage 11 for cooperation with the track 9, and automatic locking device 13 having parts, as generally disclosed in U. S. Patent 1,047,787, December 17, 1912, to J. H. Gorton, for releasably retaining the cage in normal position with respect to the hoist frame 8.

The hoist frame 8 comprises an upper cross piece 14, to which the hoisting rope or cable, not shown in the drawings, is secured; a lower distance piece 15; and, opposite upright guide channel assemblies 16, all of which may be welded, riveted or otherwise secured together, to form an upright frame having an opening 17 to accommodate the cage 11. The assemblies 16 each comprise a vertical plate 18 somewhat wider than the guide 7 with which it cooperates, and two spaced vertical angles 19, the one flange 20 of each being welded, riveted or otherwise secured to the outer face 21 of plate 18, and the other flange 22 of each engaging a side of the guide 7.

Dumping tracks 9 of the character shown in Figure 1 are common in the art and comprise spaced parallel rails 23 each having a straight portion 24 and a curved portion 25. The portions 25 curve away from the axis of the mine shaft to guide the cage 11 to a dumping position in the well known manner. These tracks 9 have been installed at many mines, at a great expense, and have a fixed position suited to the older types of cages intended for smaller cars. The portions 24 usually extend quite a distance below the curved portions 25 so as to receive the wheels 12 as the cage rises, and prevent tipping of the cage when the locking device 13 is released and before the wheels 12 reach the curved portion of the track. As may be observed from Figure 1, the portions 24 are laterally of and in close proximity to the cage at a time just before the wheels 12 reach the curved portions of the tracks.

The improved cage 11 comprises a platform 26, a substructure 27 beneath the platform, pivotally securing it to the lower portion of the hoist frame 8, and a superstructure 28 above the platform. The substructure 27 may be of any suitable character and in fact, requires no alteration in adapting the present invention to existing equipment. We have found, however, that by having the substructure 27 narrower than the platform 26 and superstructure 28, there are advantages. It gives greater clearance below the platform, the bottom of the shaft often containing rubbish, water, floating debris, etc., and it is this portion of the shaft that the substructure enters when the cage is lowered so that the platform is on a level with the track bed at the bottom of the shaft.

Generally, the substructure comprises stringers 29 and cross beams 30 on which the platform 6 is secured, depending arms 31 preferably having split journal boxes 32 on their ends, a shaft 33 mounted on posts 34 secured to the distance piece 15, the ends of the shaft 33 receiving the journal boxes 32, and substantially triangular side pieces 35 secured to the stringers 29 and arms 31.

Above the substructure 27 is the platform 26. It may be of sheet metal and is of a width so that its lateral margins 36 are in very close proximity to the channel assemblies 16. It is upon this platform that rails 37 are mounted for receiving the car 10.

The superstructure 28 is made so as to not only operate in old mine shafts and with dumping track assemblies of fixed dimensions, but also to move between the channel assemblies of old hoist frames with minimum clearance and to accommodate the wider car 10 and its topping load 38 with minimum clearance. It comprises metal side plate 40, a cross beam 41, means 42 for connecting the side plates 40 to the beam 41, and in the example shown, the dumping

wheels 12 carried by a shaft 43 supported by bearings 44 mounted on the side of cross beam 41.

Instead of using rolled metal sections such as channels, angles or I-sections, mainly to transmit movement of the dumping wheels 12 along the curved portions of track 9, to the platform 26 and substructure 27, as is common in the art, we rely mainly on the side plates 40 which may be of a gauge sufficient to resist bending or distortion, yet not occupy considerable space between the guides 7 and the channel assemblies 16. These plates 40 may also be made to give maximum protection to men riding up and down on the platform.

In the example shown, the plates 40 each have a lower marginal portion 46, preferably of the same length as the length of platform 26, upright margins 47, and converging upper margins 48 and 49, preferably terminating more to one side of the center of the plate than to the other, as shown at 50 in Figure 1. The lower margins 47 of the side plates 40 are secured to the lateral margins 36 of the platform in any suitable manner, such as by angles 51. In this way we provide a cage which will accommodate the wider mine cars allowing just sufficient clearance between the channel assemblies 16 of the frame 8 and the cage, so as to permit the latter to oscillate in the frame for a dumping and return operation, and just sufficient clearance between the plates 40 and the sides 52 of the car 10, without weakening the cage.

The beam 41 is preferably of a length less than the space between the confronting faces 53 of side plates 40. It may be made of two channel sections 54 having their flanges 55 abutting, and welded together as at 56. Thus the new cage may be made to position the dumping wheels 12 in the same location they would be if carried by an old type of cage, and to properly cooperate with old installed dumping tracks 9.

The means 42 in the preferred example of the present invention, is made to perform many functions. It comprises preferably metal strip members 58 vertically located, one at each side of the cage and secured to the side plates and to the ends of beam 41 in any suitable manner, such as by welding 59 and 60, respectively.

While not absolutely necessary, the members 58 each comprises a major portion 61, an upper minor portion 62 and a lower minor portion 63. The major portion is welded to its respective side plate; the upper minor portion extends beyond the upper portion of the side plate and is inwardly offset by bends 64 and 65, so as to meet with the end of beam 41 and not interfere with flange 66 of wheel 12; and, the lower minor portion is inwardly offset as by bends 67 and 68 and is welded as at 69 to the substructure 27. These members 58 are located so as to laterally engage the channel assemblies 16 of frame 8 when the platform 26 is in a horizontal position so as to limit swinging movement of the cage to one side only of the frame. The members 58 therefore act as means to connect the upper portions of the side plates to the beam, to maintain the upper portions of said side plates in spaced relation and against deflection; act to reinforce the side plates; act as stops for limiting movement of the cage in one direction with respect to the frame; and, act to more securely tie the superstructure to the substructure 27.

If desired, diagonal braces 70 may be provided, welded as at 71 and 72 to the beam 41 and side plates 40, respectively. These braces may be

sufficiently high so as to not interfere with the toppling load 38 of car 10.

The automatic locking device 13 is old in the art, and is shown merely by way of example. It mainly comprises an upstanding lug 73 secured to the beam 41 adjacent its central portion; latching levers 74 pivoted to upper cross piece 14 as at 75, the levers having bills 76 for engaging lugs 73 and operating arms 77, extending in opposite directions with their terminal portions 78 in the parallel planes of guides 7; and cams 80 secured to the guides 7 at faces opposite from the dumping tracks 9. Suitable springs 81 and 82 are provided to normally swing the levers 74 so that the bills 76 engage lugs 73 and thereby prevent swinging movement of the cage to the side of the frame opposite to that limited by members 58. In Figures 1, 3 and 4, the levers 74 have been shown moved, responsive to action of cams 80 cooperating with the terminal portions 78 of arms 77, to release the cage for swinging movement as the dumping wheels 12 reach the curved portions of the dumping tracks.

It is believed that the construction and operation of the improved hoist for mine cars will be understood from the foregoing description and changes in details, arrangements of parts and other modifications may be made without departing from the spirit of the invention as defined by the following claims.

We claim:

1. In a hoist for mine cars, the combination with spaced, upright, stationary guides and a hoist frame movable between said guides, provided with channel assemblies for receiving said guides, of a cage pivotally carried by the lower portion of said frame to oscillate in the frame, said cage comprising a platform for the load having its lateral margins in close proximity to said channel assemblies, a substructure beneath said platform pivotally securing the same to the hoist frame, and a superstructure above the platform comprising a cross beam of a length less than the width of said platform, side plates for each side margin of the platform, said side plates being rigidly secured to the platform and disposed next adjacent to and but slightly spaced from said channel assemblies, the confronting faces of said plates defining the lateral bounds for accommodating the mine car on the platform and the outer faces of the plates spaced from the channel assemblies just sufficient for clearance as the cage oscillates in the frame, whereby cars of maximum width consistent with spacing of the guides, may be accommodated on the platform between said side plates, a vertical support member for each side plate, said vertical support members having major portions secured to the outer faces of their respective side plates and minor inwardly offset portions extending above the upper portions of their respective side plates, said inwardly offset portions of the vertical supporting members being secured to the ends of said cross beam, and two flanged dumping wheels carried by said cross beam, said dumping wheels located one at each end of the beam and disposed with the plane of rotation of its flange in substantially the same plane as the major portion of its adjacent support member.

2. In a hoist for mine cars, the combination with spaced, upright, stationary guides and a hoist frame movable between said guides, provided with channel assemblies for receiving said guides, of a cage pivotally carried by the lower portion of said frame to oscillate in the frame,

said cage comprising a platform for the load having its lateral margins in close proximity to said channel assemblies, a substructure beneath said platform pivotally securing the same to the hoist frame, and a superstructure above said platform comprising a cross beam of a length less than the width of said platform, a side plate for each side margin of the platform, said side plates being rigidly secured to the platform and disposed next adjacent to and but slightly spaced from said channel assemblies, the confronting faces of said plates defining the lateral bounds for accommodating the mine car on the platform and the outer faces of the plates spaced from the channel assemblies just sufficient for clearance as the cage oscillates in the frame, whereby cars of maximum width consistent with the spacing of the guides, may be accommodated on the platform between said side plates, a vertical support member for each side plate, said vertical support members having major portions secured to the outer faces of their respective side plates and minor inwardly offset portions extending above the upper portions of their respective side plates, said inwardly offset portions of said vertical support members being secured to the ends of said cross beam, and said major portions positioned on said plates to engage laterally the said channel assemblies when the platform is in a horizontal position to limit swinging movement of the cage to one side only of the frame, and two flanged dumping wheels carried by said cross beam, said dumping wheels located one at each end of the beam and disposed with the plane of rotation of its flange in substantially the same plane as the major portion of its adjacent support member.

3. In a hoist for mine cars, the combination with spaced, upright, stationary mine shaft guides, a hoist frame, movable between said guides, provided with channel assemblies for sliding engagement with said guides, and two companion dumping tracks in the head frame of the shaft, said tracks located one to one side of each of said guides; of a cage pivotally mounted upon the lower portion of said hoist frame, said cage comprising, dumping wheels for cooperation with said tracks, an elongate platform for the mine car extending between and with its longitudinal margins adjacent to said channel assemblies of said hoist frame, a substructure beneath said platform pivotally securing the same to the hoist frame, and a superstructure above the platform comprising a cross-beam supporting said wheels, and a side plate secured to each longitudinal marginal portion of said platform, and to said beam, said side plates being in parallel relation, with their confronting faces defining the lateral bounds for accommodating the mine car upon the platform with just sufficient clearance to permit the car to be run onto and off the platform without lateral obstruction, and the outer faces of said plates being free of obstructions and spaced from their adjacent channel assemblies of the hoist frame just sufficient for clearance as the cage oscillates in the hoist frame responsive to travelling engagement of said wheels with said dumping tracks, whereby mine cars of maximum width consistent with spacing of the mine shaft guides, may be accommodated on the platform between said side plates.
